UNITED STATES PATENT OFFICE

2,516,521

FUEL INJECTION PUMP PLUNGER

Rowland Macdonald, Longmeadow, Mass., assignor to American Bosch Corporation, Springfield, Mass., a corporation of New York

Application March 26, 1949, Serial No. 83,663

3 Claims. (Cl. 309—4)

1
This invention relates to fuel injection apparatus and to a new and improved process of making the same.

An object of the invention is to provide a new and improved plunger for fuel injection apparatus and a process of making the same.

Another object of the invention is to provide a new and improved plunger for fuel injection apparatus and a new and improved process for accurately forming a lead thereon.

Another object of the invention is to provide a new and improved process of forming metering leads on plungers of fuel injection apparatus which provides a lead of desired accuracy and which is considerably simpler and more economical than previous processes employed for the purpose.

Other objects and advantages of the invention will be apparent from the following description taken in connection with the accompanying drawings and it will be understood that modifications may be made in the details of construction and steps of the process without departing from the scope of the invention as expressed in the accompanying claims.

Referring to the drawings:

Fig. 1 is a side view of a plunger showing a step in the process of manufacture thereof;

Fig. 2 is a view similar to Fig. 1 but showing a completed plunger;

Fig. 3 is a fragmentary view of the plunger shown in Fig. 1 but on an enlarged scale;

Fig. 4 is a fragmentary view of the construction shown in Fig. 2 but on an enlarged scale;

Fig. 5 is a development of the end of the plunger shown in Fig. 1 on which the metering lead is formed;

Fig. 6 is generally similar to Fig. 5 but shows the construction of the plunger of Fig. 2; and

Fig. 7 is a view illustrating a step in the process of forming the metering lead on the plunger.

In the manufacture of plungers for fuel injection apparatus it is necessary that the metering leads or threads which are usually in the form of a helix must be accurately formed in order that the pump may be accurately calibrated. It is the principal object of this invention to provide a new and improved plunger and a new and improved process of accurately forming the metering leads or screws thereon which simplifies the manufacture thereof and considerably reduces its cost.

Referring more particularly to the drawings wherein similar reference characters designate corresponding parts throughout the several

2
views, the plunger shown in Fig. 1 comprises the body portion 1, flange 2 and head 3.

The plunger head 3 has the vertical slot 4 formed therein and also is provided with the helix or helical shoulder 5.

The helix or helical lead 5, which is of spiral or helical form and is generally similar to a stretched out screw thread, and the lead of the helix has a definite bearing on the load range 10 of the engine and the control rack travel required to deliver a certain amount of fuel for a certain load. For example, with a plunger having a steep helix lead, it will deliver for the same control rack movement, a much greater fuel delivery that would be possible with the use of a plunger having a less steep helix lead. In actual engine application an engine requiring a relatively narrow range of load control employs comparatively less steep leads on the plunger helix and if a greater lead range is desirable, plungers with a steep helix lead are used.

The direction in which the helix runs must be either left-hand running or right-hand running and in the drawings a left-hand helix is shown by way of illustration only.

If desired, an upper helix or lead 6 may be employed for variable end of injection as well as the variable beginning of injection given by the helix 5.

30 It will be seen from the above that in order that the plunger may be so constructed as to give the desired injection characteristics to the pump, that the helix or lead 5 must be very accurately formed on the head 3 of the plunger 1.

35 In the prior constructions where this helix or lead has consisted only of the shoulder 7 shown in Fig. 3, this has been difficult as well as expensive because of the difficulty encountered in accurately grinding the shoulder 7.

40 In the plunger construction embodying the present invention as shown in Figs. 2, 4, 6 and 7, the helix or lead is formed by accurately grinding or beveling the outer edge 8 of the helix or lead which may be done with a grinding wheel as shown in Fig. 7 and which eliminates the necessity of accurately grinding the entire shoulder 7 on the helix or lead 5 thereby considerably simplifying and reducing the cost of forming accurate helices of metering leads on plungers for fuel injection equipment.

45 In the formation of the bevelled helix or metering lead 8 the use of a grinding wheel is preferable although not essential as it allows the forming of an accurate edge on a cylindrical sur-

face while using as large a grinding wheel as possible for high surface speed.

The upper helix 6 could also be so formed if desired.

In forming the bevelled lead 8, the plunger 1 may be supported by centering means 18 so constructed as to allow the moving of the plunger and wheel relative to each other and preferably the plunger 1 is helically advanced and retracted relative to the grinding wheel 9 whereby said wheel will form said bevelled edge on the shoulder 7 to thereby produce the accurate lead 8 as previously described.

From the foregoing it will be seen that I have provided a simple, efficient, accurate and economical process for carrying out the invention.

Having described my invention, I claim:

1. In a device of the character described, a plunger adapted for use in fuel injection apparatus, said plunger having a metering lead thereon, said lead comprising a shoulder having a bevelled metering edge extending throughout at least a portion of said lead.

2. In a device of the character described, a

plunger for use in fuel injection equipment, said plunger having a head portion and a metering lead in said head portion, said lead comprising a shoulder having a bevelled edge throughout at least a portion thereof.

3. In a device of the character described, a plunger for use in fuel injection equipment, said plunger having a head portion and a helical metering lead in said head portion, said helical lead comprising a shoulder and said helical lead having a bevelled edge throughout at least a portion thereof.

ROWLAND MACDONALD.
